BY *Drake & Co.* ATTY'S.

UNITED STATES PATENT OFFICE.

ROBERT H. WARREN AND DAVID WALKER, OF NEWARK, NEW JERSEY.

DESIGN FOR A STAIR-CARPET BUTTON.

SPECIFICATION forming part of Design No. 25,265, dated March 24, 1896.

Application filed February 27, 1896. Serial No. 581,069. Term of patent 7 years.

To all whom it may concern:

Be it known that we, ROBERT H. WARREN and DAVID WALKER, citizens of the United States, residing at Newark, in the county of 5 Essex and State of New Jersey, have invented and produced a new and original Design for Stair-Carpet Buttons; and we do hereby declare the following to be a full, clear, and exact description of the invention, such as 10 will enable others skilled in the art to which it appertains to make and use the same, reference being had to the accompanying drawings, and to letters of reference marked thereon, which form a part of this specification.

15 In the drawings, Figure 1 is an elevation, and Fig. 2 a sectional view, of our newly-designed stair-carpet button, taken lengthwise through the central perforation.

The leading feature of our design consists 20 in the stair-button which displays on its face series of discous ornaments disposed around the central perforation, each disk being ornamented and being interrupted in its continuity of outline toward the center of the 25 button, the button at its ends being shaped in resemblance to a fan.

In said drawings, *a* indicates the newly-designed stair-carpet button, which, in general outline, is of irregular shape.

30 *b* indicates the central perforation, and *c a*

square ornament at the center of the field of which the said perforation *b* is disposed. Around the square figure *c* is a series of small discous figures *d d d*, the upper and lower ones of which are ornamented by series of 35 small roundels *e e e* and the lateral ones by scallop-shell-like ornaments *f*. The continuity of outline of the small discous figures is broken by the central square figure. Outside of and around said small discous figures 40 are larger discous ornaments *g g g*, the outlines of which are interrupted by one another and by the smaller disks *d*. The fields of the larger disks, where they are not ornamentally occupied by the smaller disks, are ornamented by scrolls *h h* and roundels *i*.

At the opposite ends of the buttons are displayed fan-shaped ornaments *j j*.

What we claim is—

The design for a stair-carpet button here- 50 in shown and described.

In testimony that we claim the foregoing we have hereunto set our hands this 6th day of February, 1896.

ROBERT H. WARREN.
DAVID WALKER.
